GLIDER

Harry E. Wolf, Pittsburgh, Pa., assignor to Fort
Pitt Bedding Company, Pittsburgh, Pa., a cor-
poration of Pennsylvania

Application March 31, 1932, Serial No. 602,344

11 Claims. (Cl. 5—124)

This invention relates to gliders; and it comprises a knock-down glider comprising end supports having on their inner faces means for securing swinging elements and means for securing a base assembly thereto to space said end supports and form a foundation or frame, a gliding assembly comprising a frame carrying means for temporary attachment to the ends of the swinging means, and arms advantageously having portions arranged to extend over the tops of the ends or supports and having means at their lower ends for pivotal attachment to the glider frame together, advantageously, with a back having means for attachment to the glider assembly, together with the usual upholstery and cushion seat; and the invention comprises a glider such as described together with stabilizing means permitting transverse gliding of the gliding assembly and the arms but restraining endwise movement; all as more fully hereinafter set forth and as claimed.

The provision of a strong, durable and easily assembled and disassembled glider comprising relatively few parts is a desideratum in the art to which this invention relates. In order to provide mechanism permitting horizontal gliding of a portion of a settee, couch or couch-hammock glider a large number of relatively complicated and cumbersome elements have been used in the art, and in a structure which can be compactly packed for shipment, easily assembled and easily knocked down, it is usually necessary to provide bolts, nuts and other locking arrangements which increase the number of parts of the complete assembly and which are apt to become loose after the glider has been in use. Among other objects of my invention is the provision of an extremely simple knock-down glider comprising few parts, such parts being easily and securely assembled and arranged in such a way that when assembled the frames or working parts of the device are hidden from view giving the glider as a whole a pleasing appearance resembling an ordinary hammock or couch. Another object of my invention is the provision of a substantially all metal glider, the supporting parts being suitably reinforced and the end supports, base frame, gliding assembly, arms and back being of light construction, yet strong and durable, and so shaped that when the glider is disassembled or knocked down these parts may be compactly arranged for shipment and storage.

In the accompanying drawings I have shown one form of a specific embodiment of my invention.

Fig. 1 is a perspective view of the glider with parts broken away to illustrate the relation of the base and glider frame to the ends or stationary supports;

Fig. 2 is a horizontal sectional view taken above 60 the seat supporting frame, the seat and back being omitted;

Fig. 3 is a vertical section taken on line 3—3 of Fig. 2;

Fig. 4 is a transverse section taken on line 4—4 65 of Fig. 3;

Fig. 5 is a disassembled perspective view of a fragment of one of the end supports and the base before assembling;

Fig. 6 is a detail section view taken on line 70 6—6 of Fig. 3 illustrating the locking means for holding the base to the end supports;

Fig. 7 is a disassembled perspective view of a fragment of the base of the seat supporting frame 75 or the glider frame and the link which is connected to the stationary ends or supporting members;

Fig. 8 is a fragmental perspective view of one end of the seat supporting frame and the back supporting means before the back is positioned; 80

Fig. 9 is a detail section taken on line 9—9 of Fig. 2;

Fig. 10 is a disassembled perspective view of the plate attached to the base frame and the anchor plate attached by wires to the glider, 85 forming a part of the stabilizing means;

And Fig. 11 is a perspective view illustrating how the glider can be packed for shipment.

In the accompanying drawings in which similar reference numerals designate corresponding parts throughout the several views, 1 indicates the base over which the glider frame travels, such base comprising two angle iron beams suitably braced and spaced by means of bars 2 and plate 3 riveted thereto by rivets 4. The angle irons carry at each end flat plates 5 which are securely riveted in place and such plates are provided with bayonet slots 6 at their outer edges. This base assembly is arranged to be secured to the upright ends of the glider and when so secured forms a frame into which the gliding assembly is secured.

The stationary ends of the glider are preferably sheet metal plates 7 having in-turned sides and bottoms 8 for reinforcing purposes and to lend the effect of a solid panel construction, making a pleasing design. The lower center of these sides may be elevated somewhat as shown at 9 to give a pedestal effect. On the inside of each of the ends 7 are two spaced uprights 10 carry-

105

100

105

110

ing at the proper height inwardly extending headed studs 11 arranged to accommodate the bayonet slots 6 of the base assembly. When the base assembly is in position with the bayonet slots 5 over these headed studs a very rigid construction results without the necessity of using screws, bolts, nuts or the like for holding the parts together. In order to prevent vertical movement of the base with respect to the ends there are provided 10 keepers 12 consisting of metal U-shaped bars having their ends suitably bent and journaled in holes in the upright bars 10 as shown at 13. When the base has been attached to the ends through the bayonet slots 6 and the studs 11, the 15 keepers 12, which are normally in vertical position between the bars 10, are lowered to bear against the angle irons 1 comprising the main base structure.

It is desirable to provide arms which will glide 20 with the gliding assembly and it is desirable to provide a gliding assembly which will be compact and which with the arms will present a neat structure hiding the framework and the interior of the ends. The gliding assembly consists essentially of three main parts; one, the flat framework, two, the arms attached thereto, and three, the back, all of which parts are arranged for easy assembly and for easy packing when the glider is knocked down. 25 The glider frame comprises the angle iron seat supporting frame 14 (clearly shown in Fig. 2) having ends 15. Each end 15 is provided with two keys 16 arranged to be inserted over the heads of studs 17 carried by the arms. The arms 30 18 are provided with flat and turned-over tops 19 arranged to cover the upper parts of the ends 7 but not to contact therewith, and these arms are made up of the panel section 18 (designating the arms proper) attached to flat legs or standards 20 by means of rivets or by welding or the like, the standards 20 extending below the panels 18. Each standard is provided with a slotted section or end 21 which engages a corresponding slot 22 in the arm or link 23 pivotally connected 35 at 24 to the side 14 of the glider section proper. This arrangement results in a detent preventing upward movement of link 23.

Securely attached by means of rivets or welding or the like to the upper portion of the main 40 ends as at 25 are angle brackets 26 having pivoted thereto at 27 links 28 carrying headed studs 29; and preferably pivoted as at 30 to the levers 23 are shoulder brackets 31 having pivoted thereto at 32 links 33 carrying headed studs 34. Hangers 45 35 are arranged to connect the links 28 of brackets 26 with the links 33 of the levers 23 through means of the key ways 36 of the links or hanger arms 35 at either end thereof. When disassembled or knocked down the glider frame proper carries the 50 levers or links 23 with their brackets 33 in nested position, the levers 23 being swung parallel with the side bar 14. The hangers 35 are each separate pieces and the brackets 26 are permanently carried by the ends proper. The arms of the 55 glider are each separate pieces.

The back comprises an angle iron frame 37 carrying the upholstery and cover 38 and having extending arms 39 curved as shown to give the proper inclination to the back when in assembled position, as hereinafter described. Securely riveted or welded to the extremities of the frame of the back at 40 are a pair of bent tongues 41 extending beyond the frame. The ends of the frame 15 carry holes 42 into which these bent 60 tongues 41 of the back are inserted when the back 65

is in a more or less upright position. After such insertion the back is inclined rearwardly, whereupon the arms or tongues 41 engage the undersides of the ends 15 of the glider frame and the undersides of the bent ends of the back frame 39 rest upon the horizontal faces of the glider frame ends 15. The space 39A resulting from the arrangement of the sides and ends 14 and 15 of the glider frame presents a pocket into which the extremities of the back frame seat at about the points of curves, resulting in means preventing lateral sway of the back frame. This makes a rigid and steady construction and one which is easily assembled and disassembled. 80 85 90

It is advantageous to provide means to prevent lateral swinging of the glider frame and its attached parts including the back and the arms proper of the glider. For this purpose I provide a stabilator. As stated, opposite angle irons of the frame are secured together by means of a plate 3. To this plate I attach a right angle anchor bracket 43 having the keyed slot 44 in the vertical side. In removable locking engagement with such key is headed stud 45 on plate 46 having holes 47 at either end by means of which are attached the coiled spring 48 having wires 49 which are arranged to extend towards the ends of the glider frame. The glider frame is provided with a hole or other means as at 50 through which the hooked ends of the rods or wires 49 100 may be inserted. This arrangement permits swinging of the glider frame in a plane parallel to the base or to the floor upon which the glider as a whole is resting, but restrains lateral swing. The stabilator anchor with the spring coil, as 105 stated, permits a gliding movement back and forth in a plane perpendicular to the length of the frame upon which the glider as a whole rests but restrains lateral swing. 110 115 120

Through the provisions of the base frame, the glider frame, the stationary supports or ends, the arms and the back with the accessory parts described, the entire device may be easily packed as a unit and shipped as a relatively small compact 125 package. It is to be noted that the swing rods or hangers attached to the ends proper are inside the ends, that the links connecting the glider frame to the hangers may be nested into position so they are parallel with the frame sides and that the panels forming the arms are flat sections 130 which may be nested together and which may be nested with the ends proper of the glider. The arrangement of the parts is extremely simple, the ends of the glider proper being duplicates so that either may be used at either end, thus avoiding 135 confusion in assembling. The upholstered cushion seat 51 may be of any ordinary construction adapted to fit on the glider frame and may be provided with depending curtain 52 hiding the upper frame of the glider from view. The ends of the glider may be provided with handles 53 which are not only decorative but which may be used in holding the ends during assembling or in moving the glider as a whole when occasion 140 warrants. 145

The right and left hand end supports may be of stamped metal suitably reinforced as described, with the outside arranged to give a panel effect, the gliding assembly, the connecting base and the back frames may be made of angle iron with the sides of the frame suitably braced and the arms may be made of sheet metal, with the result that although the device is extremely rigid when assembled it is light in construction; and the ar- 150

angement of the parts is such that the under-
portion of the glider is completely covered by a
seat and the parts for interconnection are so ar-
ranged that it is a relatively simple matter to set
5 up the glider or take it down.

What I claim is:

1. In a glider having a base with supporting
ends and a glider frame adapted to glide over said
base, a right angled anchor bracket secured to
10 said base and provided with a keyhole slot in its
upwardly extending face, a plate carrying a
headed stud in removable locking engagement
with said keyhole slot and having holes at either
15 end and coiled springs each attached at one end
to a hole in said plate and at the other end to
wires secured to one end of the seat supporting
frame whereby transverse movement of the glider
frame with respect to the base is permitted and
lateral movement thereof restrained.

20 2. In a glider having a base with end supports
and a glider frame, stabilizing means to restrain
lateral movement of the glider frame with respect
to the base comprising a right angled anchor
bracket firmly attached to said base and pro-
25 vided with a keyhole slot in its upwardly extend-
ing face, a plate carrying a headed stud in re-
movable engagement with said keyhole slot, spring
means connecting said plate to each end of said
glider frame under tension, restraining lateral mo-
30 tion, while allowing transverse motion, and serv-
ing to retain the stud in its seat in the anchor
bracket.

3. In a glider, a gliding seat frame, arms piv-
oted near opposite ends of said frame and to op-
35 posite sides thereof and adapted to be extended
beyond the ends of said frame, link means carried
near the extremities of said pivoted arms, sus-
pensory means detachably connected to said
link means and adapted to be pivoted near the
40 top of end supporting means, and detachable end
pieces for said frame constituting arm rests of
the glider, said detachable end pieces provided
with detent means adapted to engage said piv-
oted arms in their extended positions and when
45 connected to said suspensory means.

4. In a glider having end supports, a base bridg-
ing the same and a seat gliding frame arranged
to glide over said base, stabilizing means to re-
strain end-wise movement of said gliding frame
50 comprising a spring member secured to opposite
ends of the glider frame, means on the base be-
tween its ends for attachment of said spring
member and detachable means for holding the
spring member on said last named means.

55 5. In a knock-down glider, a swingable glider
frame carrying lever arms pivoted at one end to
the frame and at the other end carrying means
for detachably engaging the lower ends of links,
links detachably attached to the carrying means
60 of said ends, and right and left hand glider arms
having in their lower portions means for detach-
able attachment to the glider frame and means
for carrying the weight of the glider frame on the
lever arms and for bracing them, whereby the
65 glider frame may be supported on end supports
by means of said links, swing on said links and
carry with it said glider arms.

6. In a glider, a swinging seat frame, ends con-
stituting glider arms adapted to be attached to the
70 ends of said seat frame, means for suspending
said seat frame and said arms from supports in
such a manner as to allow transverse swinging

motion, said suspending means comprising arms
pivoted to the side of the seat frame, links piv-
otally secured to the ends of said last mentioned
arms, additional links pivoted at right angles
to said last mentioned links, means on the last
mentioned links for engaging hanging links and
hanging links arranged for pivotal connection
to end supports.

7. In a glider, a gliding seat frame, arms piv-
oted near opposite ends of said frame and to op-
posite sides thereof and adapted to be extended
beyond the ends of said frame, link means car-
ried near the extremities of said pivoted arms,
suspensory means detachably connected to said
link means and adapted to be pivoted near the
top of end supports and detachable end pieces
carried by said gliding seat frame and consti-
tuting arm rests of the glider, and adapted when
attached to engage the pivoted arms to position
them.

8. In a glider, a glider seat frame adapted to be
positioned between two end supports and pro-
vided on each side near its ends with pivoted arms
adapted to be positioned below said frame, each
arm carrying near its extremity link means for
swinging attachment to lower ends of swinging
supporting links, swinging supporting links de-
tachably secured to the last named means, and
arm rests detachably secured to the ends of said
glider frame and having means to detachably en-
gage the lower ends of the arms which are pivoted
to the glider frame.

9. In a glider having a gliding seat frame, means
for suspending the seat frame from end supports,
said means comprising bars arranged for pivotal
attachment to end supports, arm means attached
to the gliding frame, pivoted shoulder brackets on
the ends of said arm means adapted to swing
lengthwise of the seat frame, upper links pivotal-
ly attached to the pivoted shoulder brackets and
adapted to swing crosswise of the glider frame
and pivot means for detachably attaching the
lower ends of the bars to the upper pivoted links.

10. In a glider having a gliding seat frame,
means for suspending the seat frame from end
supports, said means comprising bars arranged
for detachable pivotal attachment to end sup-
ports, arm means attached to the gliding frame,
pivoted shoulder brackets on the ends of the arms
adapted to swing in a direction lengthwise of the
125 glider, upper pivoted links attached to the pivot-
ed shoulder brackets and adapted to swing in a
direction crosswise of the glider, and means for
detachably attaching the upper pivoted links to
the lower ends of the bars.

11. In a glider, a seat frame having at each end
depending bars pivoted near the ends of the seat
frame and extending downwardly and outward-
ly therefrom, suspending means for the seat piv-
otally connected with the outer ends of the bars,
a removable end arm rest frame extending above
and below the seat frame, means at the lower end
of the arm rest frame engaging outer end por-
tions of the depending bars, means connecting
the adjacent end of the seat frame with an inter-
mediate portion of the arm rest frame to hold
the arm rest frame adjacent the seat frame and
to limit the upward movement of the arm rest
frame with respect to the seat frame whereby
the seat frame is supported on the arm rest frame
from the outer ends of the depending bars.

HARRY E. WOLF.
